VENTILATOR

James H. McDerment, Cleveland, Ohio, assignor
to The Swartwout Company, Cleveland, Ohio, a
corporation of Ohio

Application May 18, 1936, Serial No. 80,248

8 Claims. (Cl. 98—42)

This invention relates to a ventilator construction and has for its principal object to provide a superior construction for a device of this type and one which, while being relatively inexpensive, will be highly satisfactory in use and convenient of operation.

With the foregoing and other objects in view which will be in part apparent and in part pointed out hereinafter, the invention consists in all the novel features of construction and arrangement of parts hereinafter described and illustrated in the accompanying drawings wherein Fig. 1 is a transverse section taken through a ridge ventilator embodying the invention; Figs. 2 and 2a taken together make up a central longitudinal section therethrough; Figs. 3 and 3a taken together make up a horizontal section corresponding substantially to the line 3—3 of Fig. 1; and Fig. 4 is a detail fragmentary section taken through a portion of the screw threaded operating means.

In the drawings, the numeral 10 indicates a portion of the building defining a ventilating opening. Attached to the elements 10 in any suitable manner and extending upwardly and toward each other are plates 11 which are connected by spaced transverse strips 12 and bows 13. The bows 13 have portions 14 extending along the elements 11 and terminating at their lower ends in hooks 15 which are adapted to receive struck-out portions 16 of the baffle elements 17. The bows 13 are provided at their upper corners with flattened portions 18 to which are secured a ridge roll 19 and suitable bracing elements 20 and 21 which extend outwardly and position the upper edges of the baffles 17. The upper edges of the element 11 project above the strips 12 and define an opening to be closed. A damper 22 is adapted to close the opening defined by the upper edges of the element 11 and to be moved toward and from the same by the mechanism about to be described.

Secured to the bows 13 are brackets 23 to the lower edges of which and the adjacent portions 45 of the bows 13 are pivoted guide links 24. These links are pivoted at their lower ends to straps 25 which extend across and brace the damper 22. As will be obvious from the drawings, these guide links are placed opposite each other, one pair 50 to each of the supporting bows 13 and a plurality of pairs of such links are provided along the length of the damper. Each pair of guide links, pivoted to their supports and the damper in a manner to be movable while always remaining 55 parallel to each other, may be termed a parallelo-

gram guide means. Thus, the damper may be of any desired length. In view of the stresses on the elements 25, which are transmitted to the damper itself and the desirability of constructing the damper of thin sheet metal, I prefer to make 5 the elements 25 relatively wide so as to avoid kinking of the damper at the points of connection of these elements thereto.

Mounted for sliding motion on the transverse strips 12 is a reciprocating element comprising 10 spaced longitudinally extending angle members 26 and transversely extending connecting members 27 connected at their ends to the members 26 whereby to brace the latter. Pivottally connected to the members 26 and to members 28 15 which are secured to the damper immediately underneath the members 25 are a plurality of toggle members 29 each of which comprises a frame work consisting of a pair of links connected together and braced by transverse angle ele- 20 ments 30.

Attached to two of the elements 27, as will be clear from Figs. 2 and 3, I provide a connecting bar 31 to which I secure a threaded element 32. Journaled in a suitable bearing 33, carried by 25 one of the strips 12, by a sleeve 34 is a cooperating threaded element or nut 35 which is in turn connected to a tubular member 36, the rotation of which, it will be obvious, imparts longitudinal motion to the element 32. The tubular element 30 36 is journaled at its left hand end as seen in Fig. 2 in a suitable bearing 37 carried by one of the strips 12. The tube 36 has non-rotatably secured thereto a sprocket wheel 38 on which is received an operating chain 39 which extends 35 downwardly to a position readily accessible to an operator.

It will be obvious that the damper is moved upwardly from closed position by motion of the elements 26 to the left and that it will tend 40 at all times to return under the action of gravity to closed position. However, the threaded element 32 is provided with threads of such pitch that the action of gravity on the damper will not serve to rotate the element 35. Thus, 45 the damper will remain in any position at which it is set by the operator and without the necessity of any latching means.

This construction is adaptable to buildings of any length and may be constructed in sections, 50 if desired. For example, the portion shown in Fig. 2 may be considered as an operating section and the portions shown in Fig. 2a may be considered as supplemental sections and while they have been shown as of integral construction, 55

it is to be understood that the damper may be made in sections which will not be connected together and that it is only necessary to provide a connecting means for those portions of the elements 26 making up the reciprocable actuator for each section. It is of course necessary that the section shown in Fig. 2, if made separable, would have to be provided with a second pair of guide links 24 and a second actuating portion 29 mounted in the same manner as each of the two half units shown in Fig. 2a.

From the foregoing, it will be obvious that I have provided a device which is well adapted for its intended purpose and while I have shown and described the preferred embodiment, I wish it understood that my invention may be realized in varying constructions and that I am limited only in accordance with the appended claims and the prior art.

Having thus described my invention, what I claim is:

1. In a ventilator, in combination with means defining an opening to be closed, a damper, and means for controlling the motion thereof, said last means comprising a parallelogram guide means, a reciprocable element movably mounted for motion longitudinally of said damper, toggle link means actuated by sliding motion of said reciprocable element for moving said damper to and from closed position, screw means for operating said toggle link means and remote control means for operating said screw means.

2. In a ventilator, in combination with means defining an opening to be closed, a damper, and means for controlling the motion thereof, said last means comprising a parallelogram guide means, a reciprocable element movably mounted for motion longitudinally of said damper, toggle link means actuated by sliding motion of said reciprocable element for moving said damper to and from closed position, screw means for operating said toggle link means and remote control means for operating said screw means, said reciprocable element comprising spaced bars having transversely extending bracing bars connecting such spaced bars and said screw means being connected to a plurality of said bracing bars centrally thereof.

3. In a ventilator, in combination with means defining an opening to be closed, a damper, and means for controlling the motion thereof, said last means comprising a parallelogram guide means, a reciprocable element movably mounted for motion longitudinally of said damper, toggle link means actuated by sliding motion of said reciprocable element for moving said damper to and from closed position, screw means for operating said toggle link means and remote control means for operating said screw means, said reciprocable element comprising spaced bars and said toggle link means comprising similarly spaced links and provided with transversely extending bracing elements connecting them together.

4. In a ventilator, in combination with means defining an opening to be closed, a damper, and means for controlling the motion thereof, said last means comprising a parallelogram guide means, a reciprocable element movably mounted for motion longitudinally of said damper, toggle link means actuated by sliding motion of said reciprocable element for moving said damper to and from closed position, screw means for operating said toggle link means and remote control means for operating said screw means, said

reciprocable element comprising spaced bars having transversely extending bracing bars connecting such spaced bars and said screw means being connected to a plurality of said bracing bars centrally thereof and said toggle link means comprising similarly spaced links and provided with transversely extending bracing elements connecting them together. 5

5. In a ventilator, in combination with means defining an opening to be closed, a damper, and means for controlling the motion thereof, said last means comprising a parallelogram guide means, a reciprocable element movably mounted for motion longitudinally of said damper, toggle link means actuated by sliding motion of said reciprocable element for moving said damper to and from closed position, screw means for operating said toggle link means and remote control means for operating said screw means, said remote control means including a sprocket carried by said screw means and fixed to a rotatable element thereof and a flexible element carried by said sprocket and extending downwardly to a position accessible to an operator.

6. In a ventilator, in combination with means defining an opening to be closed, a damper, and means for controlling the motion thereof, said last means comprising a parallelogram guide means, a reciprocable element movably mounted for motion longitudinally of said damper, toggle link means actuated by sliding motion of said reciprocable element for moving said damper to and from closed position, screw means for operating said toggle link means and remote control means for operating said screw means, said reciprocable element comprising spaced bars having transversely extending bracing bars connecting such spaced bars and said screw means being connected to a plurality of said bracing bars centrally thereof, said remote control means including a sprocket carried by said screw means and fixed to a rotatable element thereof and a flexible element carried by said sprocket and extending downwardly to a position accessible to an operator. 35

7. In a ventilator, in combination with means defining an opening to be closed, a damper, and means for controlling the motion thereof, said last means comprising a parallelogram guide means, a reciprocable element movably mounted for motion longitudinally of said damper, toggle link means actuated by sliding motion of said reciprocable element for moving said damper to and from closed position, screw means for operating said toggle link means and remote control means for operating said screw means, said reciprocable element comprising spaced bars and said toggle link means comprising similarly spaced links and provided with transversely extending bracing elements connecting them together, said remote control means including a sprocket carried by said screw means and fixed to a rotatable element thereof and a flexible element carried by said sprocket and extending downwardly to a position accessible to an operator. 55

8. In a ventilator, in combination with means defining an opening to be closed, a damper, and means for controlling the motion thereof, said last means comprising a parallelogram guide means, a reciprocable element movably mounted for motion longitudinally of said damper, toggle link means actuated by sliding motion of said reciprocable element for moving said damper to and from closed position, screw means for operating said toggle link means and remote control means including a sprocket carried by said screw means and fixed to a rotatable element thereof and a flexible element carried by said sprocket and extending downwardly to a position accessible to an operator. 70

troi means for operating said screw means, said reciprocable element comprising spaced bars having transversely extending bracing bars connecting such spaced bars and said screw means being connected to a plurality of said bracing bars centrally thereof and said toggle link means comprising similarly spaced links and provided with transversely extending bracing elements con-

necting them together, said remote control means including a sprocket carried by said screw means and fixed to a rotatable element thereof and a flexible element carried by said sprocket and extending downwardly to a position accessible to an operator. 5
